UNITED STATES PATENT OFFICE.

CHARLES A. ERICKSON, OF STAMFORD, CONNECTICUT, ASSIGNOR TO THE
YALE & TOWNE MANUFACTURING COMPANY, OF STAMFORD, CON-
NECTICUT.

DESIGN FOR A PADLOCK.

No. 38,773.

Specification for Design.

Patented Aug. 27, 1907.

Application filed June 11, 1907. Serial No. 378,462. Term of patent 14 years.

To all whom it may concern:

Be it known that I, CHARLES A. ERICKSON, a citizen of the United States, residing at Stamford, in the county of Fairfield and State of Connecticut, have invented a new, original, and ornamental Design for Padlocks, of which the following is a specification, reference being had to the accompanying drawing, forming part thereof.

The figure is a perspective view of a padlock, showing my new design.

I claim:

The ornamental design for a padlock, as shown.

CHARLES A. ERICKSON.
